UNITED STATES PATENT OFFICE.

BENJAMIN O. PAIGE, OF LOWELL, MASSACHUSETTS.

STOP-MOTION FOR RAILWAY DRAWING-HEADS.

Specification of Letters Patent No. 31,398, dated February 12, 1861.

To all whom it may concern:

Be it known that I, BENJAMIN O. PAIGE, of Lowell, in the county of Middlesex and State of Massachusetts, have invented a new 5 and useful Stop-Motion for Railway Drawing-Heads to be Used in Cotton-Mills; and I hereby declare that the following specification, in connection with the accompanying drawings and references marked thereon, 10 constitute a lucid, clear, and exact description of the construction, application, and use of the same.

In referring to the said drawings, Figure 1, denotes a plan or top view. Fig. 2, a front side elevation. Fig. 3, an end elevation. Fig. 4, a section on line A, B, Fig. 1.

I am not aware of any invention for stop motion to a rail way drawing head and its connected cards, adjustably or otherwise, 20 and my invention or stop motion is designed expressly to prevent unevenness or improper reduction in the sliver, and to operate or stop a rail way drawing head, and carding engines connected thereto which can only 25 operate upon the cotton, or sliver, before, but not after it becomes drawing.

Invention.—The nature of my invention consists in the arrangement of hinged clearers, both above and below all the drawing 30 rollers, and coming in contact with the entire length of each of these rollers, to perform the functions of constantly cleaning or wiping them their entire length, and also to readily and certainly detect any, and the 35 least improper accumulation of sliver on any portion of any or all of the upper and lower drawing rollers, to instantly stop the railway drawing head, and all the connected cards by the adjustable connection of both 40 these same clearers, for convenience in primary construction and subsequent use; with catch lever, slide rod, and shipper arranged and operated as hereinafter described. Also, in the calender roller, carried by swinging 45 frame, and so arranged, adjustably, for convenience in primary construction, as well as subsequent use, with catch lever, slide rod, and shipper; that any partial disruption, unevenness, or material reduction of the 50 sliver will at once stop the machine and connected cards to allow for increase or to regulate the sliver, by the dropping of the calender roll, for producing and retaining a uniform sliver in the manner hereafter 55 seen, as distinguished from stop motions applied to drawing, roving, and slubbing

frames, and stopping them only when the drawing (not sliver) becomes wholly broken down.

Construction.—To enable persons skilled 60 in the art to which my invention appertains to construct and carry out the same I will describe it as follows; first stating that the railway drawing head, and its combination with a number of carding engines, 65 forms no part of my invention, neither does the stop motions applied to the drawing, roving, and slubbing frames form any part of my invention, they being constructed for 70 a different purpose, and operate in a different manner; and do not perform the function of regulating the size and weight of sliver, or drawing. The purpose of the railway drawing head is to run in connection with a series of carding engines (ten 75 more or less not shown) and to receive from them the several slivers, endless in length, made by the cards, and to condense and draw or stretch them into one by a series of rolls, the purpose of my invention being, 80 when embodied in and connected with the railway drawing head, and its connected cards, to make or produce an endless sliver of uniform size and weight its entire length by not allowing any but a suitable sliver 85 to be made.

The table of the railway drawing head, is seen at A, and its end supports at B. Two stands seen at C, are erected upon and secured to table A. In these stands I suspend the drawing rollers D, E, and F, so 90 as to freely turn or revolve therein. These rolls are geared together by gears G, and intermediates H.

I construct two clearers seen at I and J, 95 and hinge them at K, in stands C, and so arrange these clearers that they will come in contact with the entire length of all the drawing rollers D, E, and F, for two purposes, first to effectually, and constantly 100 clean or wipe these rollers their entire length and second to instantly stop the railway drawing head, and all its connected cards if any sliver accumulates on any portion of the upper or lower drawing rollers, 105 these clearers being connected, adjustably, by arm D², and rod E² with catch lever Z, operating slide rod W, and shipper U, with, and forming the stop motion, for both regulating, adjusting, and operating it in its 110 primary construction and also in its subsequent use.

The drawing rollers seen at D, are larger in diameter than, those back of them and seen at E, and so in turn those seen at E, may be larger than those seen at F, the purpose being to draw, and condense the several slivers coming from the cards, into one, and thus deliver it through guiding trumpet N, (hinged by its arm T, on rod Q,) to calendering rollers L and M, which then becomes drawing, and is delivered to revolving and receiving can, not shown.

I construct a shipper seen at U, sliding in brackets X, and X², to ship by its fork a, the belts (not shown) which drives the rail way drawing head, and parts of all the carding engines moving the sliver from the cards; this shipper is constantly pressed by spring V, in such direction, as that if unrestrained it would slide the belts (not shown) on to loose pulleys (not shown), and stop the machine, and that portion of all the cards moving the sliver, but is restrained by catch dog A³, swinging on brackets X², and catching into notch e, formed in shipper U and thus holding it, and keeping the machine, and that portion of all the connected cards moving the sliver, in operation, after the belts (not shown) are shipped on; by driving pulleys (not shown) by movement of shipper U.

I construct a slide rod W, which has a notch c, formed in its inner end into which the catch lever Z, is forced by spring A², or by its own weight when the rod W, is slid forward, and the machine or rail way drawing head and its carding engines connected are put in operation, this rod slides in brackets Y, and Y², and is constantly pressed back by spring A⁴, and when the catch lever Z, is disconnected the rod W, will instantly fly back by means of spring A⁴ and impart a percussive blow to the end i, of catch dog A³, and instantly disconnect its opposite end from notch e, in shipper U, which then instantly ships the belts by the force of spring V, on to loose pulleys (not shown) and stops the machine and that portion of all the cards, moving the sliver, and the sliver itself.

The swinging stand P, is provided with an arm B², and screw C², threaded through this arm, the lower end of which screw comes in contact with outer end of catch lever Z, so that when the sliver becomes uneven breaks down or decreases in size by breakage of its strands or otherwise the calender roll M and swinging frame P, will drop; carrying with it the arm B², and screw C², by which my stop motion is made adjustable and regulated in position both in its construction; and in its subsequent use, by turning screw C², up or down, and which screw C², when properly positioned by being so adjustable uncatches the catch lever Z, from slide rod W, and this in turn uncatches the shipper U, and the drawing

head, and that portion of all the cards moving the sliver, and the sliver itself is at once stopped, and this is effected if the sliver is either uneven, broken, or becomes improperly reduced; which is at once detected by dropping of calender roll M, which motion is transmitted by parts arranged as just described, to the shipper to operate the machines in the manner and for the purpose set forth.

The handles A⁵, and B⁵, in shipper U, and slide rod W, are for conveniently shipping the belts and putting the machines in motion. This shipper is so connected to the several carding engines (ten more or less) which are connected with the rail way drawing head; that my device stops that part of all the cards moving the sliver as well as the rail way drawing head, for governing and controlling the character of the sliver; which is effected and carried out by my arrangement and combination of frame P, with its calender roll M, stand B², and screw C², with lever Z, slide rod W, and shipper U, embodied with the rail way drawing head, in the manner described for stopping it, and that portion of each connected card that moves the sliver, whenever the latter becomes uneven or improperly reduced.

Operation.—The operation of my invention is apparent from the preceding description of construction, and the advantages so obvious that further description will be unnecessary, after simply, again calling attention to the fact that no automatic stop motion, adjustable or otherwise, and for governing and controlling the endless sliver, as to weight and size and instantly stopping the railway drawing head, and connected cards whenever the sliver is uneven or imperfect, has heretofore been invented, or applied to a rail way drawing head, and that the sliver very often breaks down in part, and frequently in the operative's absence, and causes a great waste of cotton, a delay in readjusting the sliver, and frequent breaking or disarrangement of the rail way drawing head, and delay in repairs, and stoppage of all the carding engines connected therewith, all these heretofore existing evils are obviated by my invention, by never allowing them to occur, all in the manner herein described and set forth.

Having thus described my invention, I will state my disclaimer and claim as follows.

I disclaim the stop motions heretofore applied to drawing, slubbing, and roving frames, for they are different from, and cannot be made to answer the purpose of my invention.

What I do claim as my invention and desire to secure by Letters-Patent is—

1. The arrangement of hinged clearers I and J, both above the upper, and below the lower drawing rollers D, E, and F, and coming in contact with the entire length of each of these rollers, to perform both the functions of constantly cleaning or wiping them their entire length, and also to readily and certainly detect any, and the least, improper accumulation of sliver, on any portion, of any, or all, of the upper and lower drawing rollers, to instantly stop the railway drawing head and all the connected cards, by the adjustable combination of both these same clearers, for convenience in primary construction, and subsequent use, with catch lever Z, slide rod W, and shipper U, and operated in the manner set forth.
2. The swinging frame P carrying the calender roll M, and the stand B² and screw C², when combined, and so arranged with catch lever Z, slide rod W, and shipper U, as described for regulating my stop motion in its primary construction, as well as adjusting it in its subsequent use; these parts being embodied with railway drawing head, and connected cards, and so operated by calender roll M, as to produce an even and uniform endless sliver; by instantly detecting and stopping the movement of the railway drawing head, and that portion of every connected card for moving the silver, as described, whenever the latter becomes uneven or improperly reduced.

BENJN. O. PAIGE.
